UNITED STATES PATENT OFFICE.

HOOVER HANGER, OF WASHINGTON, DISTRICT OF COLUMBIA.

ARTIFICIAL LIMB.

No. 907,146.

Specification of Letters Patent. Patented Dec. 22, 1908.

Application filed April 20, 1908. Serial No. 428,193.

To all whom it may concern:

Be it known that I, HOOVER HANGER, of Washington, District of Columbia, have invented a new and useful Improvement in Artificial Limbs, which improvement is fully set forth in the following specification.

This invention relates to the construction of artificial limbs, and has for its object to improve the construction of an artificial limb of the character shown and described in U. S. Patent to Hanger, #465,698, granted December 22d, 1891. In that patent the instep lever marked 13 is mortised in the solid part of the ankle, and the rubber bumpers or cushions marked 16 contact therewith at one end, and at the other end rest upon the solid portion of the heel of the foot. Moreover, in the actual construction of devices of this character, the said rubber bumpers have been made of pieces of rubber which were rectangular in cross-section. In practical operation it has been found that by mortising the solid ankle portion, this portion is not only more or less weakened by reason of the mortise, but that portion of the mortise lying immediately below the rear end of the instep lever 13 has been neatly filled with an inserted piece of wood. It has been found necessary to secure said instep lever, marked 13 in said patent, in place by means of screws passing through the lever and into the wood of the ankle, which still further weakens the parts. In addition to this weakening effect, it has been found that an unnecessary amount of time is consumed in neatly mortising the seat for the instep lever, inserting the required piece or block in the mortise to fill out the space below the rear end of the lever, and to finish off the rear portion of the ankle. Furthermore, it has been found that in use the rubber buffers 16 in the heel of the foot were "chewed" or worn partially in two, so that they had their elastic action decreased and eventually wore out and had to be replaced. Furthermore, since the heel portion of the foot was of wood, the limb when in actual use had the peculiar thumping wooden-leg sound which is objectionable.

The object of the present invention is to obviate the objections above noted, and to introduce certain improvements in other parts of the structure which will be more fully hereinafter described and then pointed out in the claims.

According to the present invention, the

ankle portion is not mortised for the reception of the instep lever, but there is bored through the solid portion of the ankle wood a hole into which the instep lever fits snugly, 60 and instead of being secured in place by screws as heretofore, the rear end of the lever is slightly split and a wedge driven therein, thereby firmly locking the lever in the desired position without weakening the ankle 65 portion in which it is placed or the lever itself, and the whole is performed much more neatly and with very much less skilled labor. Furthermore, by the present invention the solid heel of the foot has a vertical opening 70 cut entirely through the same, and the rubber bumper is placed in said socket or opening with its upper end resting against the solid wood of the ankle portion of the limb, while its lower end projects slightly below the 75 bottom of the heel of the foot and is held in place by a suitable heel covering of leather, preferably buckskin leather, with one or more layers of suitable cushioning material, as felt, interposed between the rubber and 80 the heel leather. I have also discovered that if a piece of rubber which is circular in cross-section is employed instead of rectangular in cross-section as heretofore, the chewing action above mentioned is eliminated. More- 85 over, the jar to the user of the limb present in the previous constructions is avoided, and the peculiar wooden-leg thumping is entirely eliminated by the cushioning action of the rubber buffer and the leather covering there- 90 for at the heel.

It has heretofore been proposed to introduce between the instep portion of the limb and the toe portion thereof suitable toe springs to give the elastic toe action to the 95 foot, this spring in some constructions being of metal and sometimes of rubber, the rubber when employed having been rectangular in cross-section and composed of a single piece. In order to get the requisite elastic 100 action, it was necessary that the piece of rubber be so large that the limited area of wood constituting the toe portion had to be largely cut away in order to provide a socket or seat for the spring therein. This mate- 105 rially weakened the foot at a point where considerable strain occurs, and in addition to this the rectangular cross-sectional form of the rubber resulted in the destructive chewing action mentioned in connection 110 with the heel bumper. In the present construction, I have obviated this difficulty by

introducing two smaller toe springs composed of rods of rubber circular in cross-section. By this means I not only avoid the destructive chewing action on the rubber, but I am enabled to employ even more of the elastic cushioning material without injuriously weakening the wood of the toe portion, since the two similar sections can be placed in similar sockets, and therefore a relatively less amount of wood is cut out of the limited toe section.

The inventive idea involved may receive a variety of mechanical expressions, one of which for the purpose of illustrating the invention is shown in the accompanying drawings, in which—

Figure 1 is a vertical central longitudinal section through the foot and ankle portion; and Fig. 2 is a perspective view, showing the parts disassembled to more fully illustrate the construction.

Referring to the drawings, 2 is the ankle portion which is hollow at its upper part, but at its lower part 3 is solid, the whole being composed of some very light wood, preferably willow, since it is essential in limbs of this construction that the two elements of lightness and strength should be combined in a single article. There is bored in a forwardly and downwardly inclined direction a hole or opening 4 in the ankle piece, and tightly fitted therein is the instep lever 5, which is necessarily composed of some very strong wood, such as hickory. The rear end of the instep lever 5 is slightly split and a wedge 6 is driven therein so as to tightly wedge the wood of the instep portion 5 into the solid wood of the ankle portion 3. It will be observed that by this construction the ankle portion below the instep lever 5 remains solid and intact as indicated at 7; that neither this ankle portion nor the instep lever 5 is weakened by means of any fastening screws or other devices to hold the instep lever in its seat; and that the work can be expeditiously performed.

The main foot portion 8 is hinged to the instep portion in the following manner: A pintle or pin 9 is secured to the ankle portion by bolts 10, which are rigidly connected to the pintle, and pass upward through the solid part of the ankle into the hollow portion 2 thereof, where they are engaged by nuts 11. Passing over the pintle 9 is a yoke 12 whose two lower arms pass downward through the wood of the foot portion 8, and are engaged by nuts 13, 13, thereby securely locking the foot to the ankle portion, but permitting a play of the foot to a limited extent around the pintle 9. For the purpose of locking the nuts 13, 13, so as to avoid accidental turning of the same, a nut lock, in the form of a block 14 is placed between the nuts and screwed to the wood of the foot by the screw 15. Any suitable means for caus-

ing the joint to work noiselessly may be provided, as for example, a suitable lining of leather 16, preferably composed of buckskin, which rests in and forms the bearing for the pintle 9 in the foot.

The heel portion has formed therein a vertical opening 17 extending entirely through the heel from top to bottom and flaring from the bottom upward, as shown, and over the opening at the bottom of the heel portion there is secured in any suitable way a leather covering 18, preferably of buckskin. Over this leather covering there may be placed, if desired, a suitable cushioning material 19 of felt, leather, or other appropriate material. In the rear lower face of the solid wood of the ankle portion 3, there is formed a socket 20, and the upper end of a piece of rubber 21, which is round in cross-section, is seated in the socket 20, with its lower end resting upon the cushioning material 19, or directly upon the leather 18 if such cushioning material be not employed.

Formed in the front end of the foot portion 8 are two sockets 22, and immediately opposite the sockets 22 in the toe portion 23 there are formed two corresponding sockets 24, and two pieces of rubber 25, substantially equal in length and circular in cross-section, are seated with their respective ends in the sockets 22 and 24, as will be readily understood from an inspection of the drawings. It will be observed that by this means a strong and effective toe spring is provided without unnecessarily cutting away the wood in the toe portion 23 to provide the sockets for the seating of the toe springs. Preferably the ball of the foot is covered by leather 26, with interposed cushioning material, as felt 27, and preferably also the cut-away portion 28 between the foot and the toe portions is covered by a suitable piece of leather 29.

It will be observed that in use the jar of the step when the heel of the foot comes against the floor or ground is absorbed by the rubber heel spring or bumper 21, and that the line of weight passes directly down through the solid ankle portion and the heel spring to the ground, without bringing any direct jar or weight upon the foot portion, and that as the ankle and other portions of the limb move forward in the act of taking a step, the said heel spring has ample opportunity for play without any chewing or abrading action against the parts. Moreover, it will be observed that by reason of the fact that the stroke of the heel against the ground or floor falls entirely upon the padded heel portion and is absorbed by the heel spring, the wooden-leg thumping, so objectionable in limbs of this character, will be entirely eliminated.

By means of the construction herein described, the limb may be made very light;

the necessary instep lever can be rigidly fixed in its position without unnecessarily weakening the ankle portion; the objectionable noises in the use of the limb are obviated; the jar upon the wearer is overcome; and the wear of the heel spring against the adjoining parts is entirely eliminated, since I have discovered that by constructing the heel spring of rubber that is round in cross-section instead of rectangular, the same may remain in use without any appreciable wear thereon. It will therefore appear that by my invention I have devised a limb that is strong, cheaply built, efficient in operation, and very durable.

What I claim is:

1. In an artificial limb, a solid ankle-piece having a forwardly and downwardly inclined bore formed therein, an instep lever wedged into said bore and projecting for-

wardly therefrom, a foot-piece hinged to said ankle-piece, and an elastic heel piece or spring on which the rear part of said ankle-piece bears.

2. In an artificial limb, an ankle-piece, a foot-piece hinged thereto and having a vertical opening through the heel portion thereof, a pliable closure for the bottom of said opening, and a heel spring formed of a piece of rubber circular in cross-section and bearing at one end on said pliable closure and at the other end on the under side of said ankle-piece.

In testimony whereof I have signed this specification in the presence of two subscribing witnesses.

HOOVER HANGER.
